US00D941523S

(12) **United States Design Patent** (10) Patent No.: **US D941,523 S**
(45) Date of Patent: ** *Jan. 18, 2022

(54) **CHILD-RESISTANT STORAGE CONTAINER**

(71) Applicant: **Sto Responsible, LLC**, Layayette, CO (US)

(72) Inventors: **Sandra Elkind**, Lafayette, CO (US); **Shuichi Amano**, Bethlehem, PA (US); **Michael Creighton**, Warrington, PA (US)

(73) Assignee: **STO RESPONSIBLE, LLC**, Lafayette, CO (US)

(*) Notice: This patent is subject to a terminal disclaimer.

(**) Term: **15 Years**

(21) Appl. No.: **29/750,041**

(22) Filed: **Sep. 10, 2020**

Related U.S. Application Data

(63) Continuation-in-part of application No. 29/673,771, filed on Dec. 18, 2018, now Pat. No. Des. 898,360, which is a continuation of application No. 16/108,903, filed on Aug. 22, 2018.

(57) **CLAIM**

The ornamental design for a child-resistant storage container, as shown and described.

DESCRIPTION

FIG. 1 is a perspective front view of a child-resistant storage container according to the present invention;

FIG. 2 is a perspective back view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines illustrate portions of the child-resistant storage container and form no part of the claimed design.

1 Claim, 4 Drawing Sheets
